CHARLES S. BATDORF, OF BROOKLYN, NEW YORK, ASSIGNOR TO PURITY CUP CORPORATION, OF NEW YORK, N. Y., A CORPORATION OF DELAWARE.

PAPER CUP.

Original application filed September 9, 1925, Serial No. 55,301. Divided and this application filed October 12, 1926. Serial No. 141,157.

This invention relates to the type of cups which is adapted for holding liquids or any other material, such for example as ice cream or the like. Heretofore paper cups, by reason of their construction, had to be made of fairly thick paper, usually freely coated with paraffin, not only because a cheap grade of paper is used but because the paraffin serves as a stiffening means for tending to hold the 5 various formations of such paper cups in set position. The method incidental to the manufacture of such paper cups usually requires the use of heavy paper stock so that the cups will stand up, and the use of moisture 10 and heat to prevent cracking while the necessary folds are being made.

Under the present invention dry and unmoistened water-resisting paper of a comparatively high grade is preferably employed, such paper being much thinner than paper previously employed for paper cups, it being possible under the present invention to make use of paper which is no greater than three thousandths of an inch in thickness, or 20 even somewhat thinner, because of the fact that the cup of the present invention is constructed in such way as to make it possible to use such thin paper. Hence, the improved 25 cups can be made much lighter than cups heretofore on the market.

Also, under the present invention a cup of special construction is provided wherein the sides or side wall of the cup has certain angular flutes, so arranged as to reinforce the cup 35 made preferably of very thin paper, and the mouth edge or lip of the cup being provided with a special beading which is so firm and compact as to be capable of resisting expansion of the lip of the cup or distortion by ordinary use; so that by reason of such flutes 40 and the beading there is provided a durable self-sustaining cup capable of convenient handling, and requiring the use of much less paper stock.

These being among the several objects of the present invention, the same consists of certain features of construction and combinations of parts to be hereinafter described and then claimed with reference to the accom-

panying drawings illustrating a preferred embodiment of the invention in which,

Figure 1 is a side elevation of the improved paper cup, which is usually smaller in size than as illustrated;

Figure 2 is a plan, looking into the cup; 55

Figure 3 is a transverse section on the line 3—3 of Figure 1, showing how the flutes commence to turn toward the body of the cup;

Figure 4 is an enlarged vertical section through one half of the cup, on the line 4—4, 60 Figure 2, for the purpose of more clearly bringing out the flutes, plaits and beading;

Figures 5 and 6 are transverse sections, respectively on the lines 5—5 and 6—6, Figure 4; 65

Figure 7 is an underside plan view of the cup; and

Figures 8 and 9 are transverse sections, respectively on the lines 8—8 and 9—9, Figure 4. 70

Referring to Figures 1 and 2, the cup is preferably made from one sheet of relatively thin paper and provided with a bottom 10 formed integrally with the side wall 11 which terminates at the lip or mouth end of the cup 75 with a beading 12. Referring to Figures 1, 4, 7, 8 and 9, the paper cup is shown as formed with a series of upwardly extending flutes 13, which are arranged in annular series or otherwise about the side wall 11 of the cup. 80 These flutes form a special feature of the present invention. It will be seen that the flutes 13 also stand outwardly or radially from the axis of the cup for a substantial distance through the height of the cup, and 85 these and intermediate portions are of preferably flattened V-shape in transverse section, that is the walls of the flutes are flattened against each other, thus tending to reinforce the cup and make it self-sustaining, 90 so as to offer resistance to the pressure of any liquid, for example, which is in the cup. Furthermore, the outwardly standing flutes 13 form somewhat rough ridges or lines of contact for the fingers of the hand which hold 95 the cup, thereby pressing into the soft flesh of the hand and enabling the cup to be held without danger of slipping from the hand

and to offer resistance against crushing by the pressure of the hand. Such flutes also offer resistance against objectionable yielding to the holding pressure of the fingers, so that 5 in practical use, that is with the cup containing a liquid, they do not crush or flatten down.

The outwardly standing flutes 13, as shown more clearly in Figures 1, 4, 5 and 6, merge, 10 in the upper part of the cup, into plaits 14 which are formed as extensions of the flutes, the flutes being gradually turned toward the main body of the cup and eventually flattened down at 15 on the intermediate portions 15 of the side wall 11 of the cup. It will be seen that at the lip of the cup the flattened down plaits 14 and the intermediate side wall portions 16 are in multiply formation and are turned outwardly, downwardly 20 and inwardly in a curl so as to form the beading 12 which reinforces the lip of the cup. At the same time the manner in which the beading is formed tends to lock and hold the plaits 14 together and prevents their unfolding. 25

The improved cup is preferably of frusto-conical shape and hence tapered toward the bottom of the cup. It will be observed that the flutes 13 are preferably so formed that as 30 a whole their outer ridges or lines of contact 17 are of greater taper than the taper of the intermediate portions 16 of the side wall of the cup; that is to say, the ridges 17 of the said flutes, from the bottom of the cup upwardly, slant away from the portions 16 of the side walls which are intermediate of the flutes. This formation imparts a gradually increased reinforcement to the cup from its bottom upwardly. It will be seen that the 35 beading 12 is formed with transverse folded edges 18 throughout its length, which are formed by the juncture between the side walls 16 and the plaits 14. It will also be seen that the flutes preferably extend above the intermediate diameter of the cup, and that the flattened down plaits at the beading follow the circumference of the lip of the cup. 40

This application is a division of co-pending application Serial No. 55,301, filed September 50 9, 1925.

It is obvious that the invention as described and illustrated is susceptible of more or less modification without departing from the scope of the appended claims.

55 What I claim is:

1. A paper cup having its side wall formed about it with a series of upwardly extending, outwardly standing, flutes, the walls of which are flattened against each other, and the outer edges of which, from the bottom of the cup upwardly, slant away from the portions of the side wall which are intermediate the flutes. 50

2. A tapering paper cup, the smaller end of which is at the bottom, and the wider end is

at the lip, and the cup having its side wall formed about it with a series of upwardly extending, outwardly standing, substantially non-yieldable and non-crushable flutes, the outer edges of which have a greater taper toward the lip of the cup than the portions between the flutes. 70

3. A paper cup having its side wall formed about it with a series of upwardly extending, outwardly standing, substantially non-yieldable and non-crushable flutes, said flutes extending above the intermediate diameter of the cup and terminating in flattened plaits which follow the circumference of the lip of the cup. 75

4. A paper cup, comprising a side wall and a beading at the lip, the side wall formed about it with a series of upwardly extending, outwardly standing substantially non-yieldable and non-crushable flutes, said flutes extending above the intermediate diameter of the cup, and terminating in flattened plaits, said plaits successively overlapped at their terminals, whereby the beading is formed from the terminals of the plaits and of the intermediate portions of the side wall. 80

5. A paper cup, comprising a side wall and a beading at the lip, the side wall formed about it with a series of upwardly extending, outwardly standing, flutes, which are of substantially flattened V-shape in cross-section, said flutes extending above the intermediate diameter of the cup and the flutes being over-turned, and terminating in flattened plaits, and the beading formed from the terminals of the plaits and of the intermediate portions of the side wall, the outer edges of the said flutes converging from the plaits toward the bottom of the cup. 95

6. A paper cup, comprising a side wall and a beading at the lip, the side wall formed about it with a series of upwardly extending, outwardly standing, substantially non-yieldable and non-crushable flutes, said flutes extending above the intermediate diameter of the cup, and being over-turned and terminating in flattened plaits before reaching the beading, and the beading formed from the terminals of the plaits and of the intermediate portions of the side wall, the cup tapering and the outer edges of the flutes having a greater taper than the portions between the flutes. 100

7. A paper cup having its side wall formed about it with a series of upwardly extending, outwardly standing, substantially non-yieldable and non-crushable flutes, said flutes extending above the intermediate diameter of the cup and being over-turned and terminating in plaits which are flattened plaits and overlapped following the circumference of the lip of the cup, and means for holding and binding the plaits in flattened down position. 115

8. A paper cup tapered toward the bottom and having its side wall formed about it with 120

a series of upwardly extending, outwardly standing, substantially non-yieldable flutes which are substantially of flattened V-shape in cross-section.

5 9. A paper cup, the side wall of which is formed about it with a series of upwardly extending, substantially non-yieldable and non-

crushable flutes, the flutes being laterally over-turned and flattened into plaits at the top of the cup before reaching the rim of the 10 cup, and the plaits and the adjacent portions of the wall of the cup being formed into a beading at the rim of the cup.

CHARLES S. BATDORF.
